(57) CLAIM

The ornamental design for a card cover, as shown and described.

DESCRIPTION

FIG. 1 is a perspective view of the first embodiment of the card cover showing our new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a perspective view a second embodiment of the card cover;

FIG. 9 is a front view thereof;

FIG. 10 is a back view thereof;

FIG. 11 is a left-side view thereof;

FIG. 12 is a right-side view thereof;

FIG. 13 is a top view thereof; and,

FIG. 14 is a bottom view thereof.

The broken line showing of portions of the card cover is included for the purpose of illustrating environmental structure and forms no part of the claimed design.
